(No Model.)

J. H. PENDLETON, A. BRYSON, Jr., C. TIERS & L. MOSS.
ENDLESS BELT FOR GRIPS FOR CABLE RAILWAYS.

No. 404,500.

Patented June 4, 1889.

UNITED STATES PATENT OFFICE.

JOHN H. PENDLETON, OF BROOKLYN, AND ANDREW BRYSON, JR., CORNELIUS TIERS, AND LINCOLN MOSS, OF NEW YORK, ASSIGNORS TO THE RAPID TRANSIT CABLE COMPANY, OF NEW YORK, N. Y.

ENDLESS BELT FOR GRIPS FOR CABLE RAILWAYS.

SPECIFICATION forming part of Letters Patent No. 404,500, dated June 4, 1889.

Application filed November 13, 1888. Serial No. 290,740. (No model.)

To all whom it may concern:

Be it known that we, JOHN H. PENDLETON, of Brooklyn, in the county of Kings and State of New York, and ANDREW BRYSON, JR., CORNELIUS TIERS, and LINCOLN MOSS, of the city, county, and State of New York, have invented an Improvement in Endless Belts for the Grips of Cable Railroads, of which the following is a specification.

10 In an application for patent for grips for cable railways, filed July 21, 1888, by J. H. Pendleton, A. Bryson, Jr., and Cornelius Tiers, Serial No. 280,658, there is shown and described, but not of itself claimed therein, an 15 endless belt against which the cable is pressed when the grip is clamped to the cable.

The present application for patent relates to the construction of said endless belt.

The object of our present invention is to 20 provide an endless belt for a cable-grip which will not injure the cable by contact therewith, and which in its turn will not be rapidly worn and injured by the cable. We accomplish this by making the endless belt of a band or 25 bands of leather, or leather and canvas combined, or of canvas alone, or of a steel band or bands, having blocks of leather or other yielding material secured thereto for the cable to come into contact with. Said blocks

30 form the outer portion of the belt, and each block is composed of a number of pieces of leather or other yielding material riveted together and placed upon the band or body portion of the belt, so that the end grain of the 35 leather or the edges of the strips of yielding material form the outer face of each block. The end grain of the leather gives a yielding surface, in which the cable embeds itself when the grip is applied; but this surface is not

40 quickly worn by the contact of the cable. The outer faces of the blocks are grooved in line with each other, so that there is a nearly semi-circular groove extending entirely around the belt, and the cable occupies this groove in 45 the portion of the belt that is below the supporting-drums of the belt when the grip is applied, and said groove prevents the cable moving sidewise in the grip. The back of the endless belt is provided with metal plates

to protect said back from wear against the 50 stationary portion of the grip.

In the drawings, Figure 1 is an elevation of the endless belt and its supporting-drums and a portion of the grip. Fig. 2 is a section at the line $x x$ of Fig. 1. Fig. 3 is a longitudinal section of a portion of the belt. Fig. 4 is an elevation of one of the metal plates for the back of the belt. Fig. 5 is a cross-section. Fig. 6 is a longitudinal section, and Fig. 7 an elevation of modifications in the 60 belt.

As this endless belt is especially designed for use with a grip for cable railways, we have shown said belt in connection with a cable-grip, so that the object of the peculiar construction of the belt will be fully understood; but we remark that said belt may be used with other forms of grip than that represented in the drawings, and that it may be used for other purposes than in a cable-grip. 70

The body portion f of the endless belt may be a chain, or it may be of wire rope or of a single thickness of leather or of canvas, or a steel band or bands may be used; but we prefer that it be made of two or more thicknesses 75 of leather with a band of canvas f^5 between each two thicknesses of leather.

f^4 are the blocks which form the outer portion of the endless belt. Each block is composed of a number of layers of leather, or of 80 leather and rubber canvas alternating with the leather. These layers are cut out by a suitable cutter to the proper shape, and then the desired number of layers are brought together and secured by rivets f^8 . 85

The blocks f^4 are placed upon the band f side by side with a slight space between the blocks, and the layers of leather or other material f^{12} stand crosswise of the belt, as shown in Figs. 2 and 5, and upon their edges, as seen 90 in Figs. 3, 6, and 7, so that the end grain of the leather will be at the outer surfaces of the blocks and form yielding and elastic surfaces for the endless cable C to come in contact with.

The blocks f^4 are connected to the band f by the same pins or rivets f^6 that connect the metal plates f^7 to said band. These metal

plates f^7 form the back or inner portion of the endless belt, and they are preferably of malleable cast-iron, and there is one of these metal plates at the back of the band f immediately opposite each block f^4 , the plates and blocks being of the same length and breadth. Each plate has four pins f^6 , that may be cast with said plate, and these pins are passed through holes made in the band f and in the blocks f^4 , and the ends of said pins f^6 are spread or riveted up, as shown, after the pins have been passed through the band and block, so that they firmly secure both the plate and the blocks to the band.

15 Each block f^4 has a nearly-semicircular groove in its outer face, and this groove is central of the block and longitudinally of the belt, so that a groove is formed that extends entirely around the belt of blocks. This groove may be formed in the blocks by a suitable cutter before the blocks are secured to the band f ; or the layers of leather forming the blocks may be cut with the proper opening to form the groove when the layers are put together. The endless belt, when used with a grip like that shown in said application Serial No. 280,658, is mounted upon drums f' on shafts $f^2 f^2$, and the belt is to be put in motion when the grip is to be applied, so as to have the endless belt moving at about the same surface speed as the traveling cable, as set forth in said application, and to which application reference is hereby made for a more detailed description of the operation of the grip and belt.

35 When the cable C is lifted by the hook d^3 of the moving part of the grip, said cable is brought into contact with the grooved portion of the endless belt and lifts the belt as it travels below the drums, so that the back of said belt is brought into contact with and slides on the shoe $\tilde{b}$, secured to the stationary part of the grip. The endless belt continues to move with the cable until its motion is arrested by the pressure of the back of the belt against said shoe, caused by the hook d^3 pressing against the cable, and the latter in its turn pressing the belt against the stationary shoe $\tilde{b}$.

50 Instead of riveting up the ends of the pins f^6 to secure the block f^4 and plate f^7 to the band f , the same result may be accomplished by passing a wire f^{13} through each two pins f^6 and through the block f^4 , as shown in Fig. 5, the ends of the wires being bent over outside the block to confine them in place. By this arrangement a block f^4 , if injured, can be quickly removed by simply withdrawing the wires f^{13} , and then removing said block from the pins f^6 .

To prevent the blocks f^4 being spread by the pressure of the cable, each block may be

inclosed at its sides by a metal case f^{14} , said case being secured to the block by screws or by the pins f^{13} , that may pass also through 65 said case and be bent down outside thereof.

In Fig. 6 we have shown metal bands f^9 as forming part of the body portion f of the endless belt. These bands are preferably of steel, and when these bands are at the inner portion 70 of the belt, as shown, the plates f^7 are dispensed with.

We claim as our invention—

1. The combination, with the band f , forming the body of the belt, of the blocks f^4 , of 75 layers of leather or similar material, secured to the same and forming the outer portion of the endless belt, substantially as and for the purposes specified.

2. The combination, with the band f , forming the body portion of the belt, of the blocks f^4 upon the outer portion of the band, metal plates at the inner part or back of said band, and means for securing the blocks and plates to the band, substantially as set forth. 80

3. The combination, with the band f and blocks f^4 upon the outer portion of the same, of the metal plates f^7 at the inner part of said band f , and pins passing through the band and blocks for securing the plates and blocks 90 to the band, substantially as set forth.

4. The combination, with the band f , blocks f^4 , and plates f^7 , having pins passing through the band and blocks, of wires f^{13} , passing through said pins and blocks, substantially as 95 and for the purposes set forth.

5. The combination, with the band f , blocks f^4 , and plates f^7 , having pins passing through the band and blocks, of the metal case f^{14} around the sides of each block, substantially 100 as specified.

6. The combination, with the band f , forming the body portion of the belt, of the blocks f^4 upon the same, each block being composed of layers of leather or other yielding material 105 riveted together and secured to said band with the layers perpendicular to the band, substantially as and for the purposes set forth.

7. The combination, with the endless band f , forming the body portion of the belt, of 110 metal plates f^7 at the inner part of said band, and blocks f^4 , of leather or similar material, upon the outer portion of said band, each block having a semicircular groove in its outer face, substantially as and for the purposes set forth. 115

Signed this 10th day of November, 1888.
